US00D791794S

(12) United States Design Patent (10) Patent No.: US D791,794 S
Gaggiotti et al. (45) Date of Patent: * Jul. 11, 2017

(54) DISPLAY SCREEN OR PORTION THEREOF WITH GRAPHICAL USER INTERFACE

(71) Applicant: NET ENTERTAINMENT MALTA SERVICES LTD., Ta'Xbiex (MT)

(72) Inventors: Lorenzo Gaggiotti, Johanneshov (SE); Anders Lokrantz, Stockholm (SE)

(73) Assignee: Net Entertainment Malta Services, Ltd., Ta'Xbiex (MT)

() Term: 14 Years

(21) Appl. No.: 29/491,572

(22) Filed: May 22, 2014

(30) Foreign Application Priority Data

Mar. 21, 2014 (EM) 00242970-0002

(51) LOC (10) Cl. 14-04

(52) U.S. Cl. USPC D14/486

(58) Field of Classification Search

USPC D14/485-495

CPC H04M 1/72547

See application file for complete search history.

(57) CLAIM

The ornamental design for a display screen or portion thereof with graphical user interface, as shown and described.

DESCRIPTION

FIG. 1 is a front view of a first embodiment of a display screen or portion thereof with graphical user interface showing the new design; and,

FIG. 2 is a front view of a second embodiment of a display screen or portion thereof with graphical user interface showing the new design.

The broken line perimeter illustrates a display screen or portion thereof and forms no part of the claimed design.

1 Claim, 2 Drawing Sheets
